US00D990434S

(12) **United States Design Patent** (10) **Patent No.:** **US D990,434 S**
Fu et al. (45) **Date of Patent:** **** Jun. 27, 2023**

(54) **SWITCH**

(71) Applicant: **SCHNEIDER ELECTRIC (AUSTRALIA) PTY LTD**, Macquarie Park (AU)

(72) Inventors: **Jiayu Fu**, Shenzhen (CN); **Youliang Zhang**, Shenzhen (CN); **Dahai Zhang**, Shenzhen (CN); **Zhen Ma**, Shenzhen (CN)

(73) Assignee: **Schneider Electric (Australia) PTY LTD**, Macquarie Park (AU)

(**) Term: **15 Years**

(21) Appl. No.: **29/783,910**

(22) Filed: **May 17, 2021**

Related U.S. Application Data

(62) Division of application No. 29/703,890, filed on Aug. 30, 2019, now Pat. No. Des. 925,469.
